(57) **CLAIM**

The ornamental design for a handgun, as shown and described.

DESCRIPTION

FIG. 1 is a first isometric view of the handgun;
 FIG. 2 is a second isometric view thereof;
 FIG. 3 is a left side elevational view thereof;
 FIG. 4 is a right side elevational view thereof;
 FIG. 5 is a front elevational view thereof;
 FIG. 6 is a rear elevational view thereof;
 FIG. 7 is a top plan view thereof; and,
 FIG. 8 is a bottom plan view thereof.

The portions of the handgun depicted in broken lines form no part of the claimed design.
